BRASSIÈRE WITH BREAST STRAPS HAVING
ADJUSTMENT AT SIDESJack J. Lo Cascio, Bayonne, N. J., assignor to
Even-Pul Foundations, Inc., New York, N. Y.,
a corporation of New York

Application April 2, 1951, Serial No. 218,775

1 Claim. (Cl. 2—42)

1

This invention relates to new and useful improvements and structural refinements in brassières, and the principal object of the invention is to provide a brassière having breast pockets equipped with breast supporting straps for the purpose of imparting proper contour and uplift to the breasts, an important feature of the invention residing in the provision of means at the opposite sides of the brassière for adjusting the breast supporting straps, so as to vary the degree of uplift which is imparted thereby to the breasts.

Another feature of the invention resides in the specific construction of the breast supporting straps which are elastic to facilitate a certain amount of stretching, but which also include protective means to safeguard against any possibility of pinching the skin when the straps are partly or fully contracted.

Some of the advantages of the invention reside in its extreme simplicity of construction, in its convenient and expeditious adjustability, in its pleasing appearance, and in its adaptability to economical manufacture.

With the above more important objects and features in view and such other objects and features as may become apparent as this specification proceeds, the invention consists essentially in the arrangement and construction of parts as illustrated in the accompanying drawings, in which:

Figure 1 is a perspective view of the invention in use;

Figure 2 is a fragmentary inside elevational view of the invention per se;

Figure 3 is a fragmentary sectional detail, taken substantially in the plane of the line 3—3 in Figure 2;

Figure 4 is a fragmentary sectional view, taken substantially in the plane of the line 4—4 in Figure 1; and

Figure 5 is a fragmentary sectional detail, taken substantially in the plane of the line 5—5 in Figure 2.

Like characters of reference are employed to designate like parts in the specification and throughout the several views.

Referring now to the accompanying drawings in detail, the invention consists of a brassière which is designated generally by the reference character 10 and embodies in its construction a front portion or section 12 including a pair of breast cups 14 connected together at the center of the front portion by a vertical strip member 16, the outer side edges of the breast cups 14, in turn, being connected by elastic inserts 18 to

a pair of side portions or sections 20 which extend around the sides to the back of the brassière and are suitably connected together.

A pair of elastic straps 22 are disposed in lower portions of the respective breast cups 14 and have inner ends thereof stitched to the vertical strip member 16 of the brassière front portion 12, the straps 22 extending downwardly and laterally across the respective breast cups and the inserts 18 at the inside of the brassière, but outer end portions of the straps 22 project outwardly from the brassière through vertical slots 24 with which the side portions 20 are provided, as shown.

Adjustable fastener means are employed for connecting the outer ends of the straps 22 to the side portions 20, these fastener means preferably being of the type disclosed in Patent No. 2,437,765, granted to N. Statham on March 16, 1948. The adjustable slide 26 of the fastener means is provided at the outer end of each strap 22 for sliding movement on the fastener track 28 which is provided on a strip-like base 30 stitched between the inner and outer walls 32, 34, respectively, of the side portions 20, as is best shown in Figure 4. The outer walls 34 of the side portions 20 are slotted so as to expose the fastener tracks 28, and it will be apparent from the foregoing that by simply adjusting the position of the fastener slides 26 on the tracks 28, the tension of the straps 22 may be varied accordingly, thereby proportionately increasing or decreasing the shaping action or uplift imparted by the straps 22 to the breasts. By virtue of the usual configuration of the breast cups 14, the straps 22 actually underlie the breasts so that proper uplifting effect is achieved.

Attention is now particularly directed to the specific construction of the straps 22, each consisting of a stretchable elastic band 36 which is completely enclosed in a stretchable, textile jacket 38. The jacket 38 may either be flat tubular in form, or may be in the nature of a strip which is wrapped around the band 36 and has its longitudinal edges stitched together as well as to the band, as indicated at 40 in Figure 5.

In any event, while the jacket is being applied to the elastic band, the elastic band is fully contracted and the jacket is applied thereto in its fully contracted form, the walls of the jacket being continuously flat. Then, when the strap assembly is stretched, the jacket stretches with the elastic band, while preserving its flat continuity, so that when the strap assembly is ultimately returned to its contracted form, no shirring of the jacket takes place.

The jacket 38 is preferably in the nature of

jersey material, or the like, which, while preserving its flat form during expansion and stretching, prevents any possibility of pinching of the skin by elastic or stirring action.

It may be noted that while in the instant invention the straps 22 of this specific construction are disclosed in association with a brassière, such straps may also be employed in other similar environments, wherever an elastic band is used so as to come in contact with the skin.

It is believed that the advantages and use of the invention will be clearly understood from the foregoing disclosure, and, accordingly, further description thereof at this point is deemed unnecessary.

Having described the invention, what is claimed as new is:

A brassière including a front section comprising a pair of breast cups having contiguous inner edges thereof secured together by a vertical line of stitching, a pair of elastic inserts secured to the outer edges of the respective breast cups, a pair of side sections secured to the respective inserts and extending around the sides to the back of the brassière, front edge portions of said side sections being provided adjacent their lower edges with a pair of vertical slots, a pair of elas-

- tic straps secured by said line of stitching to the inside of said front section at a point spaced substantially upwardly from the lower edge of the front section, said straps extending downwardly and laterally to opposite sides of said line of stitching across the respective breast cups and the respective inserts and projecting slidably through the respective slots to the outside of the brassière, the outer end portions of said straps 5 being superposed longitudinally on the respective side sections, and longitudinally adjustable means 10 for connecting the outer end portions of the straps to said side sections.

JACK J. LO CASCIO.
